AIR CONDITIONING APPARATUS

Samuel M. Anderson, Sharon, Mass., assignor to
 B. F. Sturtevant Company, Hyde Park, Mass.,
 a corporation of Massachusetts

Application January 13, 1933, Serial No. 651,519

13 Claims. (Cl. 183—17)

The present invention relates to air conditioning apparatus and more particularly to apparatus of the general type described in my co-pending application patented Nov. 21, 1933 Patent 5 #1,936,243.

The principal object of the present invention is to reorganize and improve the construction of air conditioning apparatus of the general type disclosed in said application, particularly with relation to facility of construction and assembly.

With this object in view, the present invention comprises the air washing apparatus hereinafter described and particularly defined in the claims.

In the accompanying drawings, which illustrate what is now considered the preferred form of the invention, Fig. 1 is a vertical sectional elevation of a portion of the apparatus; Fig. 2 is a horizontal section on line 2—2 of Fig. 1; Figs. 3 and 4 are perspective views of the eliminator assembly; Fig. 5 is a detail, vertical, sectional view on line 5—5 of Fig. 1; Fig. 6 is a detail, horizontal, sectional view of the mounting of the inlet filter; Fig. 7 is a perspective view showing the mode of attachment of vertically adjacent units; Fig. 8 is a detail sectional view showing the preferred connection for the water supply; and Figs. 9 to 13 are detail views of a modified construction.

The illustrated embodiment of the invention includes a bottom collecting chamber 10 and a plurality of superposed conditioning or washer units, each indicated generally at 12.

The collecting chamber comprises end walls 14 and side walls 16, the latter being provided with a drain or overflow connection 18 and a return connection 20 to be connected with the spray pump. The chamber is divided by a thin transverse plate 22, connected between angles 24 attached to opposite side walls 16. The plate serves as a positioning stop for the filter supporting member of the lowermost washer unit, as will hereinafter be described. An additional set of angles 25 is arranged near the other end of the chamber to permit the chamber to be reversed with respect to the superposed washer unit, while still affording means for attachment of the plate 22 in the same position with relation to the washer unit. This provision for mounting the collecting chamber in either position is important since it permits the water connections to be made on either side of the apparatus.

Attached to the upper parts of the walls 14 and 16 are transverse and longitudinal angle members 26 and 28 respectively, and internal opposed angles 30 and 32 are attached thereto, as shown in Fig. 1, thereby forming a continuous upwardly

facing channel extending completely around the upper part of the chamber.

The lowermost conditioning or washer unit 12 has side walls 34, each provided at the bottom with a horizontal bolting flange 36, cooperating with a flange 37 on the side wall of the collecting chamber 10 (see Fig. 7). The washer unit is similarly formed with flanges at the top to permit superposition of an additional unit thereon. At the bottom of the washer unit 12, a continuous angle member or sill 38 extends completely around the unit, the bottom edge of the sill 38 abutting the top edges of the angles 28 and the end walls 14 of the collecting chamber. Internal angle flanges 40 are attached to the sills 38 and are disposed around the four sides of the unit, these angles 40 having depending portions somewhat longer than the sills 38 in order to overlap and fit closely around the internal angle pieces 30 and 32 of the collecting chamber. The joints between the depending angles 40 of the washer unit and the upstanding angle flanges 30 and 32 of the collecting chamber unit are sealed with solder.

At the front or air inlet face of the casing, that is, the right-hand face, as viewed in Fig. 1, is the inlet filter screen 42 of the same general construction as described in my said co-pending application, comprising front and rear reticulated faces between which is metal wool of some non-corrodible material, such as copper. The filter is supported in the following manner:—The bottom edge of the filter rests on the sills 38. The inner vertical sides of the filter abut against angle irons 44 secured to the side walls 34. At the top, the filter abuts against a longitudinal angle piece 46.

The filter is held in place by means of a baffle frame indicated generally at 48. This frame comprises two vertical channel members 50 to engage the opposite side walls of the casing, the inwardly turned flange portions 52 thereof pressing against the filter (see Fig. 2). Extending horizontally across the washer are a plurality of eliminators or baffles 54, each comprising a plate downwardly inclined toward the filter and having at its outer end a hook 56 to prevent the outward passage of water through the air inlet in the event that the spray is turned on when the air supply is cut off. Each baffle is provided at its ends with turned-up tabs 57, and the tabs are riveted to the channel members 50.

The bottom portion of the baffle frame is held in place by an angle piece 59 secured to one of the sills 38. The frame is secured to the casing at opposite sides by bolts 60. In order to remove the

filter, either for a replacement thereof, or for access to the spray nozzles, it is merely necessary to unbolt the baffle frame, swing the top out, and lift the bottom over the angle 59. The filter is then free to be pulled out. The top and bottom corners of the frame adjacent the filter are cut away, as shown in Fig. 1, to permit the frame to be tipped outwardly for removal.

The air, after passing in the direction of the arrow through the filter 42, enters the spray chamber 61, where it is subjected to a mist of water ejected from the spray nozzles 62. The nozzles are mounted on separate pipes 63, as shown in my co-pending application, each of the pipes being connected into a supply pipe 66 which is connected to a suitable water supply in a manner to be hereinafter described in detail.

After passing the sprays, the air continues through an outlet filter 68 and thence through a series of eliminators, indicated generally at 70, for the purpose of eliminating entrainment.

The outlet filter 68 is of the same construction as the inlet screen 42, and is positioned internally against two vertical angle pieces 72 attached to the casing. The bottom of the filter rests upon a plate 74, the ends of which are supported on the horizontal surfaces of the sills 38. Extending downwardly from the front end of the plate 72, that is, the right-hand end as viewed in Fig. 1, is a vertical apron 76 which abuts against the plate 22 of the collecting chamber around the filter. At the rear, the plate 74 is formed with an upward extension 77 which engages the rear side of the filter. The upward extension 77 is only a sufficient height to position the filter, without preventing its insertion or removal.

The eliminator frame, as shown in Fig. 4, comprises two vertical box-like structures 78, forming the sides, which are snugly received within the casing and which abut against removable positioning members consisting of angle pieces 80 extending around the two sides and the top of the washer, and bolted thereto. This box structure 78 is constructed of a single piece of metal forming the three vertical walls, and two pieces of metal forming the top and bottom walls which are connected to the side walls by the tabs 84 turned inwardly therefrom.

Connected between the boxes 78 is a top wall construction to which the eliminator plates are attached. This top wall construction comprises a rear vertical plate 86 connected at its bottom with a forwardly extended plate 88 having outwardly extended tabs 90 arranged to be bolted to the top pieces 82 of the box 78. In front of the plate 88 is disposed a second vertical piece 91 and a horizontal plate 92, and another or third vertical plate 94, all forming the step-like structure of Fig. 3. This construction for the top of the eliminator is preferably made of a single piece of metal.

The bottom of the eliminator frame comprises the single plate 96. The eliminators comprise three series of vertical baffles in zig-zag arrangement, as shown in Fig. 2, one series being attached to the forward plate 92, and one series to the rear plate 88, as shown in Fig. 3. Each baffle consists of a single sheet of metal 98 having three connected right angle portions. A vertical, inwardly facing hook 100 is formed along the entire rear edge of each plate and vertical hooks 102 and 104 are attached to the first and second outer corners respectively of each plate. The baffles are arranged side by side, as shown in Fig. 3,

each being provided with suitable riveting tabs 105.

Attached between the plate 94 and the bottom plate 96 are a pair of filter holding channels 106, each having a back plate 107 attached to the eliminator frame and a front plate 108 to engage the filter. Bolts 109 passing through the side walls 34 engage threaded plates 110 welded to the inside of the box structure 78 to secure the eliminator frame in position.

The eliminator frame is held in place at the bottom by a vertical ledge 111 attached to the sill 38. To remove or replace the filter, it is only necessary to remove the bolts 109 and swing the top of the eliminator frame out and lift the bottom over the ledge 111. The angle pieces 80 are then unbolted and removed, thus providing a clear space to swing the filter out over the positioning plate 77.

The top of each washer unit is built in a manner exactly similar to the top of the collecting chamber 10, namely, by the use of outside angle pieces 112 and 113 corresponding to the angle pieces 26 and 28 of the collecting chamber and by internal angles 114 similar to the angles 30 of the collecting chamber, thereby forming a complete upwardly facing channel extending completely around the washer. The upper or rear vertical plate 86 of the eliminator frame abuts against and is positioned by the angle 112.

The upper part of the first washer unit therefore presents to the second washer unit the same construction as is presented to the first washer unit by the collecting chamber and the attachment between the washers is made in a fashion similar to the attachment of the first washer unit to the collecting chamber. A filter apron 116 similar to the stop apron 76 is provided in the second washer and extends downwardly over the face of the first filter in the same manner as the apron 76 engages the plate 22 of the collecting chamber.

In operation, the air flowing through the apparatus is constrained to pass through both filters and both sets of eliminators and baffles. Any entrained water is collected on the filters and eliminators and courses downwardly through the unit next below, eventually running into the collecting chamber. It will be noted that the space 117 in rear of the apron 116 of any washer unit is a dead air space, which permits any water to flow downwardly to the section below without disturbance from the air stream. Similarly, the space in the rear of the plate 22 in the collecting chamber is a dead air space, the plate preventing any flow of air around the filter.

A feature of importance in connection with the piping of the sprays is shown in Fig. 8. The main spray supply pipe of the washer unit is shown at 66. This pipe is threaded into a coupling member 120 which is attached to the side wall 34 of the washer unit by bolts 122. A gasket 124 and a bolting ring 125 are placed respectively on the inside and outside of the wall. The inlet feed connection comprising a pipe 126 is threaded directly into the coupling 120. It will be noted in this construction that the gasket 124 is required to seal only against the slight air pressure in the chamber and is not required to withstand the high water pressure as is usual coupling arrangements.

The construction above described is particularly suitable for apparatus made of galvanized iron, in which welded joints cannot be employed. The present invention, however, with some minor

changes, is adapted for a cheaper construction, in which some welded joints are used. This construction is shown in Figs. 9 to 13 inclusive.

The construction of the joints between adjacent units of the apparatus is shown in Fig. 12. The upper end of each washer unit is formed of a horizontal ledge 130 extending completely around the unit. This ledge is formed with an upstanding portion 132, a horizontal portion 134 and an outer vertical portion 136 forming means to receive and position the eliminator frame 138 which is of substantially the same form as the eliminator 70 previously described. The bottom portion of the superposed washer unit has a ledge 140 which engages the ledge 130 and an inverted U-shaped sill structure 142 having its outer side 144 abutting with the vertical portion 136 of the lower unit. The ledges 130 and 140 are coated with a water-proof plastic material and are secured together by bolts 146. The apron 148 which supports the filter immediately above and engages the filter of the unit below is mounted similarly to the apron 116 of Fig. 1. An angle 150, similar to the angle 111 of the construction of Fig. 1, is provided to position the lower end of the eliminator frame.

The filter 152 is positioned in side channel members 154 as indicated in Fig. 11, one side of the channel being reduced in size to permit the filter to be removed. The frame of the eliminator 138 comprises a side plate 156 from which extends inwardly the plate 158 having an inturned edge 160 to engage and position the filter. The eliminator plates are secured to the frame as in the construction previously described.

A modified water connection is shown in Fig. 9. The spray pipe 161, which is similar to the pipe 66 of the construction previously described, is fitted at each end with the plug member 162 of a union. The threaded member 164 of the union is welded to a ring 166 which in turn is welded to the side wall of the casing, the welds being indicated at 167. With this construction, the pipe 160 may be cut to the proper length, regardless of any variations in the size of the unit, and the pipe may be easily sprung into place, after which the nuts 168 of the unions may be taken up. The water connection 170 may be made at either side of the unit, the other side being plugged. As in the first modification, the joints between the wall and the fitting are required to withstand only the small pressure existing within the chamber. The welds and areas adjacent thereto are protected by asphaltum paint. This modified connection is somewhat simpler and is more accessible for repairs, but is preferably not used on apparatus which has been constructed of galvanized iron because of the damage to the galvanized surface.

The welded construction permits use of an advantageous form of overflow pipe shown in Fig. 13. The ordinary overflow frequently permits the water to run out in a vortex, thereby introducing variations in the load on the pump and militating against uniformity of operation. According to this invention, the overflow comprises a bent tube 174 conveniently in the form of a 45° coupling which is welded to the interior of the collecting chamber. It has been found that the water in passing outwardly through the curved tube is unable to form a vortex and therefore runs without rotation into the pump.

Having thus described the invention, what is claimed is:

1. Air conditioning apparatus comprising a conditioning unit having sills surrounding the unit and of downwardly facing channel form, and a collecting unit having sills surrounding the unit and of upwardly facing channel form with portions to overlap the sills of the conditioning unit. 5

2. Air conditioning apparatus comprising a conditioning unit having sills of downwardly facing channel form, a collecting unit having upwardly facing channels with portions to overlap the sills of the conditioning unit, a filter in the conditioning unit, an apron on which the filter is supported and having a portion extending downwardly into the collecting unit, and means associated with the apron to prevent by-passing 10 of air around the filter. 15

3. Air conditioning apparatus comprising a casing having sills, a filter, angle pieces internally of the casing to position the filter, an eliminator comprising a frame and a plurality of 20 baffles, one of the sills having a vertical ledge, and means for positioning the frame within the ledge to lock the filter. 20

4. Air conditioning apparatus comprising a plurality of conditioning units, each including a 25 filter, a collecting unit, a support for the filter of each conditioning unit having an apron extending into the unit next below, and means in the collecting unit to engage the apron to prevent by-passing of the air around the filter. 30

5. Air conditioning apparatus comprising a casing, a filter, positioning means for the filter, an entrainment eliminator comprising a plurality of baffles, each having a plurality of angle 35 portions, the frame for the eliminator comprising a bottom plate and a step-like upper plate, a channel attached to each side of the frame for locking the filter, and means for securing the frame in the casing. 35

6. Air conditioning apparatus comprising a 40 casing, a filter, filter positioning members internally of the casing, an eliminator frame to engage the filter on the side opposite to the filter positioning members, means for detachably positioning the eliminator frame at the lower end to the casing to permit the frame to be swung into place, and means at the upper end of the frame for securing it in the casing. 45

7. Air conditioning apparatus comprising a 50 casing, a filter, filter positioning members internally of the casing, removable frame positioning members on the opposite side of the filter, and an eliminator frame having a portion extending inwardly beyond the frame positioning members 55 to engage the filter. 55

8. Air conditioning apparatus comprising a 60 casing having at the bottom a vertical ledge, a filter, internal filter positioning members, a frame to engage and secure the filter, the frame being held between the ledge and the filter, and means for securing the frame in place in the casing. 60

9. Air conditioning apparatus comprising a 65 casing having at the bottom a vertical ledge, frame positioning members disposed inwardly of the casing, and an eliminator frame having portions extending inwardly beyond the positioning members, the frame being mounted between the ledge and the positioning members. 65

10. Air conditioning apparatus comprising a 70 collecting unit, a superposed conditioning unit, a filter, means for positioning the filter in the conditioning unit, a plate on which the filter is supported having an apron depending into the collecting unit, and a positioning stop plate in the 75

collecting unit to be engaged by the apron to prevent by-passing of air around the filter.

11. Air conditioning apparatus comprising a plurality of superposed conditioning units, a filter for each unit, eliminators behind the filters, plates on which the filters are supported, sills for supporting the plates, the plate for an upper unit having an apron depending into the unit below to engage the face of the filter to form a space through which the water may flow downwardly from the upper eliminator without disturbance from the air.

12. In air conditioning apparatus, a collecting chamber having water connections at one side, a conditioning unit mounted on the collecting chamber, plate supporting means on opposite sides of the chamber and near opposite ends there-

of, and a plate to divide the collecting chamber and adapted to be attached to either pair of supporting members on opposite sides of the chamber, whereby the collecting chamber may be reversed with respect to the conditioning unit.

13. Air conditioning apparatus comprising a plurality of superposed units, each unit having a top, a horizontal ledge and an outer vertical portion extending around the unit, and at the bottom a horizontal ledge and a sill of downwardly facing channel form extending around the unit, two of such units being connected together with the horizontal ledges attached and the downwardly facing sill portion of the upper unit opposed to the vertical portion of the lower unit.

SAMUEL M. ANDERSON.
